UNITED STATES PATENT OFFICE.

VERN L. JONES, OF DETROIT, MICHIGAN, ASSIGNOR TO THE FARRAND COMPANY, OF DETROIT, MICHIGAN, A CORPORATION OF MICHIGAN.

PNEUMATIC ACTION FOR MUSICAL INSTRUMENTS.

1,201,306.

Specification of Letters Patent.

Patented Oct. 17, 1916.

Application filed April 10, 1913. Serial No. 760,255.

To all whom it may concern:

Be it known that I, VERN L. JONES, a citizen of the United States of America, residing at Detroit, in the county of Wayne 5 and State of Michigan, have invented certain new and useful Improvements in Pneumatic Actions for Musical Instruments, of which the following is a specification, reference being had therein to the accompanying drawings.

10 My invention relates to pneumatic actions for automatic pianos and more particularly to that type of action composed of a series of motor and valve units.

15 The invention consists in the provision of a simple and efficient structure which may be easily and cheaply manufactured; in a structure that is compact and reduces the width of the action; in a construction that 20 is not easily affected by change in atmospheric conditions, and in certain combinations and arrangements of parts as will more fully hereinafter appear.

25 In the drawings, Figure 1 is a vertical, central section through one of the pneumatic units embodying my invention; Fig. 2 is a similar view taken in a different plane; and Fig. 3 is a top plan view.

30 A designates one of the units composed of a valve section or unit B and a key-actuating pneumatic C, and D is the wind-trunk to which the units of one series are attached. 35 Each valve section comprises a casing E, preferably cylindrical and formed of metal, and primary and secondary pneumatics arranged therein. Thus the primary pneumatic is formed of a chest section having a lower member F and an upper member G. The lower end of the casing is closed by a 40 metallic cap H provided with a chamber I to which a conduit J that leads to the tracker-board, is connected. A suitable washer K is interposed between the cap H and the flange L upon which the cap is seated, so as 45 to seal the joint therebetween.

M is a diaphragm suitably attached to the upper face of the cap H and closing the top of the chamber I and N is a valve positioned within a recess or chamber O and controlling a passage P.

50 R is a second valve connected to the stem a of the valve N and controlling communication between the passage P and a chamber Q in the upper member G. The chamber O 55 is connected by means of a conduit S in the

chest section of the primary pneumatic and an aperture T in the casing with the wind-trunk. Leading from the passage P is a conduit U that opens into the diaphragm chamber V of the secondary pneumatic, this 60 diaphragm chamber being formed in the top face of the upper member G. The diaphragm W of the secondary pneumatic is arranged between the adjacent faces of the primary and secondary chest sections and 65 preferably is attached to the upper member G of the primary pneumatic. The member X is chambered at Y and the latter is in constant communication with the wind-trunk by a passage Z and an aperture A' in 70 the casing E.

B' is the upper member of the secondary pneumatic chest, herein shown as formed of a ring section C' and a metallic disk D'. Communication between the chamber E' of 75 the member B' and the chamber Y is controlled by a valve F' and attached to be simultaneously operated with the valve F' is a second valve G' that controls an aperture H' in the disk D'. 80

I' is a clamping ring having a screw-threaded engagement with the casing E and adapted to clamp the several parts within the casing. The joints between the cap and the ring C' and between the latter and the member X are sealed by packing rings 85 J' K'.

The chamber Q is in communication with the atmosphere by means of a passage L' that alines with an aperture M' in the side 90 of the casing E, and the joint between the casing and the member G around the aperture M' is sealed by means of a packing ring N' preferably made of felt, seated in a recess N² in the member G. The conduit J is 95 provided with a bleed connection (not shown) which is in communication with the exhaust mechanism.

In operation the parts are normally as 100 shown in Fig. 1, and since the chambers O I and Y are in communication with the exhaust mechanism, these chambers will be at less than atmospheric pressure. Also since the diaphragm chamber V is in communication with the chamber O by means of the 105 passage P and conduit U, the diaphragm chamber will be at less than atmospheric pressure. Upon the opening of a port in the tracker-board which leads to the tube J, the chamber I will be placed in communication 110

with the atmosphere, thereby causing the raising of the diaphragm M which will close the valve N and open the valve S. Upon the opening of the valve S the chamber Q which 5 is in communication with the atmosphere by way of the port L' and aperture M' will be connected to the diaphragm chamber V by means of the passage P and conduit U, expanding the diaphragm, closing the valve 10 G', and opening the valve F'. The opening of the valve F' places the key-actuating motor C in communication by means of apertures Q' R' and the aperture S', with the chamber Y and therefore, in direct communication with the wind-trunk D. The 15 vacuum will collapse the pneumatic C in the usual manner. Upon the closing of the port in the tracker-board that leads to the tube J, the bleed connection for the tube J will 20 exhaust the chamber I, permitting the valves to return to their normal position. Upon the opening of the valve G' the pneumatic C is placed in communication with the atmosphere through the aperture H', 25 chamber E' and ports Q' R'.

It will be noticed that when the port S' is open the key-actuating pneumatic is in communication with the wind-trunk by a very short passage. This materially 30 increases the speed at which the instrument may be played, since the shorter the passage, the quicker will the vacuum of the wind-trunk act upon the key-operating pneumatics.

35 The construction of valve section hereinbefore described permits the parts of the primary and secondary pneumatics to be readily assembled within or removed from the casing. When assembled the pneumatic 40 parts are supported by the flange L and are secured in place by a single clamping member—the ring I'. In making up the unit the washer L is attached to the bottom face and the diaphragm M to the top face of the 45 metallic cap H; the pouch or diaphragm W

is secured to the member G and after the valves of the primary pneumatic are engaged with the member F the latter and the member G are cemented together. The pneumatic is positioned in the casing and 50 the member X arranged thereon. The valves of the secondary pneumatic, the ring C', washers K' J' and disk D' are properly engaged with each other. Then the ring I' is screwed into the upper end of the casing 55 to clamp the several parts in place. As all the joints between the abutting faces of the primary and secondary pneumatics are sealed, and as the washers L and J' seal the joints of the end members of the casing, 60 an exceedingly accurate fit between the side walls of the chest sections and the sides of the casing is unnecessary.

The wind-trunk D is secured to the casing E by means of a screw A² passing through 65 an aperture in the trunk and having the inner end engaging a threaded aperture B² in the casing. A suitable packing as C² is interposed within the trunk and adjacent the connection between the trunk and the 70 casing so as to properly seal the joint therebetween.

What I claim as my invention is:—

In a pneumatic action, a valve unit, including a casing and primary and secondary 75 pneumatics chests arranged in said casing, a wind-trunk on one side of said casing adapted to communicate with said primary and secondary pneumatics, and a key-actuating pneumatic on the opposite side of said cas- 80 ing adapted to communicate with said secondary pneumatic, the passage between said key-actuating pneumatic and said wind-trunk being comparatively short and direct.

In testimony whereof I affix my signature 85 in presence of two witnesses.

VERN L. JONES.
